UNITED STATES PATENT OFFICE

RAYMOND E. PATTEN, OF OAK PARK, ILLINOIS, ASSIGNOR TO EDISON ELECTRIC APPLIANCE COMPANY, A CORPORATION OF NEW YORK

DESIGN FOR A COMBINED CLOCK FRAME AND FACE

Application filed December 31, 1929. Serial No. 33,987. Term of patent 14 years.

To all whom it may concern:

Be it known that I, RAYMOND E. PATTEN, a citizen of the United States, residing at Oak Park, in the county of Cook, State of Illinois, have invented a new, original, and ornamental Design for a Combined Clock Frame and Face, of which the following is a specification, reference being had to the accompanying drawing, forming a part thereof.

The accompanying drawing shows in Fig.

1 a front elevation and in Fig. 2 a side elevation of a combined clock frame and face embodying my new design.

I claim:

The ornamental design for a combined clock frame and face substantially as shown.

In witness whereof, I have hereunto set my hand this 20th day of December, 1929.

RAYMOND E. PATTEN.
